DOOR KNOCKER

John J. Bourgeois, Southington, Conn., assignor to Emhart Corporation, Bloomfield, Conn., a corporation of Connecticut

Filed Oct. 12, 1964, Ser. No. 82,135

Term of patent 14 years

(Cl. D10—7)

Fig. 1.

Fig. 2.

Fig. 4.

Fig. 3.

Fig. 5.

FIG. 1 is an elevational side view of a door knocker embodying my new design, the opposite side being a mirror image of that shown.

FIG. 2 is an elevational front view thereof.

FIG. 3 is a bottom plan view of said door knocker.

FIG. 4 is an elevational front view of the back plate of said door knocker.

FIG. 5 is an elevational rear view of the striker plate of said door knocker.

I claim:

The ornamental design for a door knocker, substantially as shown.
